HOLDER FOR FOOD BOWL FOR PETS

Tony Robert, 5701 Southwest Freeway,
Houston, Tex. 77027

Filed July 10, 1972, Ser. No. 269,953

Term of patent 14 years

Int. Cl. D30—03

U.S. Cl. D30—13

FIG. 1 is a top, front, side perspective view of a holder for food bowl for pets showing my new design, the turn lock being in a closed position;

FIG. 2 is a side view of same in a closed position;

FIG. 3 is a bottom view of the same;

FIG. 4 is a rear view showing the side opposite that of FIG. 1; and

FIG. 5 is a side view similar to that of FIG. 2 the turn lock being in an open position.

A portion of FIG. 1 has been shaded to indicate contrast in appearance.

I claim:

The ornamental design for a holder for food bowl for pets, as shown and described.
